GRINDING MACHINE

Charles C. Alvord, Worcester, Mass., assignor to Norton Company, Worcester, Mass., a corporation of Massachusetts

Application December 23, 1954, Serial No. 478,110

3 Claims. (Cl. 51—134.5)

The invention relates to grinding machines, and more particularly to a speed control apparatus automatically to maintain a uniform peripheral speed of the grinding wheel as it wears away.

One object of the invention is to provide a simple and thoroughly practical speed control mechanism automatically to maintain a substantially uniform peripheral speed on a grinding wheel. Another object is to provide an automatically actuated rheostat control for varying the speed of the grinding wheel driving motor so as to maintain a substantially constant peripheral speed of the wheel as it wears away. Another object is to provide an automatically actuated speed control mechanism which is actuated by and in timed relation with the truing tool feeding mechanism for increasing the rotative speed of the grinding wheel as it wears away so as to maintain a substantially constant peripheral speed thereon. Another object of the invention is to provide a cam actuated mechanism for controlling a standard rheostat or potentiometer automatically to maintain a uniform peripheral speed of the grinding wheel as it wears away. Other objects will be in part obvious or in part pointed out hereinafter.

In the accompanying drawings in which is shown one of the various possible embodiments of the mechanical features of the invention:

Fig. 1 is a fragmentary side elevation of a grinding machine embodying the invention;

Fig. 2 is a hydraulic diagram of the actuating mechanism for the truing apparatus;

Fig. 3 is an electric wiring diagram of the control apparatus;

Fig. 4 is a fragmentary side elevation, on an enlarged scale, partly broken away and shown in section, through the truing apparatus;

Fig. 5 is a fragmentary front elevation, on an enlarged scale, of the truing apparatus;

Fig. 6 is a fragmentary rear elevation, on an enlarged scale, showing the cam and rheostat together with the actuating mechanism therefor;

Fig. 7 is a fragmentary sectional view on an enlarged scale, taken approximately on the line 7—7 of Fig. 6 through the actuating cam and the follower; and

Fig. 8 is a fragmentary sectional view, on an enlarged scale, taken approximately on the line 8—8 of Fig. 6 through the rheostat actuating mechanism.

A grinding machine has been illustrated in the drawings comprising a base 10 which serves as a support for a rotatable work support (not shown). This work support may be identical with that shown in the prior U. S. Patent No. 2,522,485 to H. A. Silver and C. G. Flygare, dated September 12, 1950, to which reference may be had for details of disclosure not contained herein.

The base 10 serves as a support for a transversely movable wheel slide 11 which is arranged to slide transversely on a V-way and flat way (not shown) formed on the upper surface of the base 10.

A grinding wheel feeding mechanism is provided for imparting a transverse movement to the wheel slide 11 relative to the base 10 comprising a half-nut 14 depending from the underseite of the wheel slide 11. The half-nut 14 meshes with or engages a rotatable feed screw 15. The feed screw 15 may be actuated by any of the well

2

known conventional feeding mechanisms, either manually or automatically.

The wheel slide 11 serves as a support for a rotatable grinding wheel spindle 16 which is journalled in spaced bearing (not shown). The wheel spindle 16 supports a grinding wheel 17 at one end thereof. The grinding wheel 17 is partially surrounded by a wheel guard 18 which is fastened to the wheel slide 11.

A suitable driving mechanism is provided for the spindle 16 comprising a variable speed electric motor 20 which is mounted on the upper surface of the wheel slide 11. The motor 20 is provided with a motor shaft 21 having a multiple V-grooved pulley 22 mounted thereon which is connected by multiple V-belts 23 with a multiple V-grooved pulley 24 which is mounted on the right hand end of the wheel spindle 16. A rheostat or potentiometer 25 having an actuating shaft 26 (Fig. 6) is provided for varying the speed of the motor 20.

The wheel guard 18 supports a housing 30 having a plane upper surface which in turn supports a bracket 31 for supporting a grinding wheel truing apparatus. A slide base 32 is fixedly supported on the bracket 31 by means of clamping screws 33 and 34. The slide base 32 serves as a support for a longitudinally movable slide 35 which is arranged to slide longitudinally on a dove-tailed slide-way 36 (Fig. 4) formed on the slide base 32.

A hydraulically operated mechanism is provided for traversing the truing apparatus slide longitudinally comprising a cylinder 37 which contains a slidably mounted piston 38. The piston 38 is connected to the left hand end of a piston rod 39 (Fig. 2), the other end of which is fastened to an end cap 40 fixedly mounted on the right hand end of the slide 35 (Fig. 2). A pair of nuts 41 serve to lock the piston rod 39 to the end cap 40. The end cap 40 is provided with an adjustable stop screw 42 which is arranged to engage the right hand end of the cylinder 37 when the slide 35 is traversed longitudinally toward the left (Fig. 2). When fluid under pressure is passed through a pipe 45 into a cylinder chamber 46, the piston 38 together with the slide 35 will move toward the right (Fig. 2). During this movement of the piston 38 fluid within a cylinder chamber 47 may exhaust through a pipe 48.

A control mechanism is provided for controlling the admission to and exhaust of fluid from the cylinder 37 comprising a rotary type valve 50 having a valve rotor 51 which may be actuated manually by a control lever 52. When fluid is passed through a pipe 53 from a suitable source of supply, it passes into a valve chamber 54, through a transverse passage 55 in the rotor 51 into a valve chamber 56 and through the pipe 48 into the cylinder chamber 47 to cause the piston 38 to move toward the left. This movement of the piston 38 and the slide 35 toward the left continues until the stop screw 42 engages the right hand end of the cylinder 37. During this movement of the piston 38 toward the left, fluid within the cylinder chamber 48 may exhaust through the pipe 45 into a valve chamber 57, through a transverse passage 58 in the valve rotor 51, into a valve chamber 59 and out through an exhaust pipe 60 and through a throttle valve 61. By manipulation of the throttle valve 61, the speed of movement of the piston 38 and the truing apparatus slide 35 may be readily varied and controlled as desired.

When it is desired to reverse the direction of movement of the slide 35, the control lever 52 may be shifted in a clockwise direction into the broken line position 52a (Fig. 2) which movement shifts the valve rotor 51 so that fluid under pressure from the pipe 53 passes into the valve chamber 57, through the pipe 45 into the cylinder chamber 46 to cause the piston 38 and the slide 35 to move longitudinally toward the right. During this

movement fluid within the cylinder chamber 47 may exhaust through the pipe 48 into the valve chamber 56, through the transverse passage 55 into the valve chamber 54 and out through the pipe 60 and the throttle valve 61.

The longitudinally movable slide 35 serves as a support for a vertically arranged housing 64. The housing 64 is provided with spaced bearings 65 and 66 (Fig. 4) which support a vertically arranged truing tool carrier 67 having a truing tool 68 mounted at its lower end.

A feeding mechanism is provided for feeding the carrier 67 vertically in either direction relative to the longitudinally movable slide 35. This mechanism may comprise a nut and screw feeding mechanism in which a threaded portion 69 is provided on the upper end of the carrier 67. A rotatable nut 70 meshes with or engages the threaded portion 69 and is provided with an integral flange 71 which is rotatably supported on the carrier 64 by a pair of plates 72 and 73.

A manually operable feed wheel 75 is mounted on the lower end of a vertically arranged rotatable shaft 76 which is rotatably supported in a housing 77. The housing 77 is fixedly mounted relative to the housing 64. The upper end of the shaft 76 is provided with a pinion 78 which meshes with a gear 79 keyed on the periphery of the nut 70. It will be readily apparent from the foregoing disclosure that a rotary motion of the hand wheel 75 will be imparted through the mechanism above described to rotate the nut 70 and thereby impart a vertical axial movement to the truing tool carrier 67. The direction of rotation of the hand wheel 75 serves to determine the direction of movement of the carrier 67. In order to facilitate locking the carrier 67 in an adjusted position, a spring pressed detent 80 is provided which is arranged to engage the teeth of a gear 81 keyed on the upper end of the shaft 76. When it is desired to adjust the position of the truing tool 68, the detent may be moved in a direction toward the left (Fig. 4) to disengage the detent from the gear 81 after which the feed wheel 75 may be rotated to cause the desired vertical movement of the truing tool carrier 67 and the truing tool 68.

As shown in Fig. 3, power lines 84 and 85 are provided for supplying electric power to the grinding wheel driving motor 20. A start switch 86 is provided which when closed serves to energize a relay switch 87 which when energized serves to pass current to the rheostat 25 to start the motor 20. A stop switch 88 is provided whereby the motor 20 may be stopped at any time during a grinding operation if desired.

In order to attain the main object of this invention, it is desirable to provide an automatic control mechanism for the rheostat 25 so that as the grinding wheel is reduced in diameter due to wheel wear and wheel truing, an increase in speed is obtained by advancing the rheostat 25 automatically. In the preferred construction the rheostat is preferably controlled by the down feeding movement of the truing apparatus so that when the truing tool is fed toward the operative peripheral surface of the grinding wheel 17 for a truing operation, a corresponding motion is imparted to the rheostat control shaft 26 so as to adjust the rheostat as the grinding wheel wears away. In the preferred construction a conventional type rheostat is provided and a cam controlled mechanism is interposed between the truing tool feeding mechanism and the rheostat shaft so that as the wheel wears away a compensating adjustment is provided for the rheostat to maintain a uniform peripheral speed. As illustrated in the drawings a flexible shaft 90 is connected by a coupling 89 with the upper end of the shaft 76. The lower end of the flexible shaft 90 is connected to a driveshaft 91 of a gear reduction unit 92. The gear reduction unit illustrated is of a standard commercial variety such as manufactured by the Boston Gear Works having a 150 to 1 reduction between the drive shaft and the driven shaft. The gear reduction unit 92 is provided with a driven shaft 93 (Fig. 7) which supports a cam plate 94 having a spiral cam groove 95

formed therein. A follower roller 96 rides in the cam groove 95 and is supported by a stud 97 on a slide bar 98. The left hand end of the slide bar 98 is provided with an elongated slot 99 which is arranged to slide upon the rear end of the driven shaft 93 of the gear reducer unit 92. The other end of the slide bar 98 is slidably supported within a bracket 100 which is in turn supported by a bearing 101 on the rheostat control shaft 26. The slide bar 98 is provided with rack teeth 102 which mesh with a pinion 103 which is keyed onto the rheostat shaft 26. The spiral cam groove 95 is so shaped as to control the rate of actuation of the rheostat shaft 26 in relation to the down feed of the truing tool so as to maintain a constant peripheral speed of the grinding wheel as it wears away. It will be readily apparent from the foregoing disclosure that when the truing tool is fed vertically in a downward direction for a truing operation, a compensating adjustment will be imparted through the mechanism above described to advance the rheostat so as to maintain a constant peripheral speed on the grinding wheel.

It will thus be seen that there has been provided by this invention apparatus in which the various objects hereinabove set forth together with many thoroughly practical advantages are successfully achieved. As many possible embodiments may be made of the above invention and as many changes might be made in the embodiment above set forth, it is to be understood that all matter hereinbefore set forth, or shown in the accompanying drawings, is to be interpreted as illustrative and not in a limiting sense.

I claim:

1. In a grinding machine having a transversely movable wheel slide, a rotatable wheel spindle thereon, a grinding wheel on said spindle, means including an electric motor on said slide to rotate said spindle, a rheostat on said slide operatively connected to control the speed of said motor, a truing apparatus on said slide including a longitudinally movable slide movable parallel with the axis of the wheel spindle, a transversely movable truing tool carrier on said slide, feeding mechanism interposed between the truing apparatus slide and the carrier to feed the truing tool toward and from the grinding wheel, means including a cam and a rotatable follower operatively connected to actuate said rheostat, and operative connections between the truing tool feeding mechanism and said cam whereby actuation of the truing tool feeding mechanism automatically actuates the rheostat to adjust the speed of said motor, said cam being shaped to control rate of actuation of the rheostat so as to maintain a constant peripheral speed of the grinding wheel as it wears away.
2. In a grinding machine as claimed in claim 1, in combination with the parts and features therein specified in which the cam and follower mechanism comprises a slide bar to support said cam follower, and a rack and gear connection between the slide bar and rheostat to actuate said rheostat so as to maintain a constant peripheral speed of the grinding wheel as it wears away.
3. In a grinding machine as claimed in claim 1, in combination with the parts and features therein specified of a gear reducer unit on said slide having a driving and a driven shaft, operative connections between the truing tool feeding mechanism and the drive shaft, a cam on said driven shaft, a rotatable follower roller engaging said cam, a slide bar to support said follower roller, and a rack and gear connection between the bar and rheostat to actuate said rheostat to adjust the speed of the motor so as to maintain a constant peripheral speed of the grinding wheel as it wears away.
